UNITED STATES PATENT OFFICE.

WARD B. STORY, OF NEW YORK, N. Y., ASSIGNOR TO AMERICAN ASSEMBLING MACHINE COMPANY, A CORPORATION OF DELAWARE.

OPENING DEVICE.

1,249,851.

Specification of Letters Patent. Patented Dec. 11, 1917.

Application filed November 16, 1916. Serial No. 131,673.

To all whom it may concern:

Be it known that I, WARD B. STORY, a citizen of the United States, and a resident of New York city, in the county of New York and State of New York, have invented 5 certain new and useful Improvements in Opening Devices, of which the following is a specification.

This invention relates generally to opening 10 devices for folded paper sections and is particularly designed for use in connection with newspaper assembling machines.

In the art of assembling or "stuffing" 15 newspapers as recently practised the most successful devices have embodied members movable toward and from each other for acting on an intermediate folded paper section supported in a vertical position with its fold lowermost, to first initially open the 20 paper section and then engage the initially separated parts of the section and move them away from each other to complete the opening of the section. Opening devices of this general type are shown in Patents No. 25 1,202,270 October 24, 1916 and No. 1,202,914, October 31, 1916. The principal object of this invention is to produce an improved and simplified device, of the general type referred to, for opening folded paper sections 30 with a greater certainty of operation and at a greatly increased speed.

Having in view this general object, the invention consists partly in the provision of means for making use of an air blast as 35 a feature of the opening operation; in mounting the mechanism for performing the initial separating operation on one of the opening members and actuating it by the direct thrust of the opposite member 40 and without the use of an especially provided actuating means; and in providing means for stretching one of the folds of the section taut to facilitate the opening of the remaining section. Other features of the 45 invention will be referred to as the specification proceeds.

In the accompanying drawing, in which the invention is disclosed in a concrete and preferred form, like reference characters 50 are used to designate like parts.

Figure 1 is a side elevation, partly broken away, of a portion of a machine embodying the invention.

Fig. 2 is a front elevation of the device looking from the right of Fig. 1. 55

Fig. 3 is a detailed view showing the switch mechanism.

Fig. 4 is an enlarged detailed view showing one of the opening devices.

Fig. 5 is a transverse vertical sectional 60 view of the opening device looking in the direction of the arrow at Fig. 4.

Fig. 6 represents a transverse vertical section of the machine taken along the line 6-6 of Fig. 1. 65

Fig. 7 is a horizontal sectional view taken along the line 7-7 of Fig. 1.

In the preferred embodiment of the invention chosen for illustration there is shown an opening apparatus of the general type 70 already referred to, in which opening members are provided which are movable toward and from each other for acting on an intermediate folded paper section, supported in a vertical position with its folded edge lowermost, to first initially open the paper section and then to engage the initially separated folds of the section and move them outwardly away from each other to complete the opening of the section. In this 75 invention means for utilizing a blast of air in the opening operation have been incorporated, as well as improved mechanism for initially opening the paper section, and means for stretching one of the folds of the 80 folded paper section taut in order to facilitate the buckling of the remaining fold to initially open the section. The opening mechanism described is particularly adapted to be used in connection with the assembling machine disclosed in application Serial No. 131,674, filed Nov. 16, 1916. 85

In Fig. 1 of the drawing a side elevation is shown of a machine showing the general organization of the device. The principal 90 operating parts are represented generally by a movable supporting member 1 on which the lowermost folded edge of the paper section rests as it passes down through the machine from the feeding mechanism located 100 overhead and represented generally by the feed rolls 2 shown in Fig. 3 of the drawing. As the paper passes down between the guide members 3 the vertical folded edges thereof pass by a nozzle 4 of the air blast pipe 5 105 through which air is blown between the sides

of the folded paper section to straighten out the leaves of the section, to remove wrinkles and folds therefrom and to prevent the collapse of the section. The folded paper section continues to be fed downwardly between the guide members 12 and thence between the separated rear paper clamps 7 and the separated opening members or jaws 8 and 9 to its position of rest on the supporting members 1. The opened position of the jaws 8 and 9 is indicated at the right hand of Fig. 2 of the drawing and it will be seen that a pair of feeding-out rollers 10 and 11 also take a separated position along with the opening members 8 and 9 so that no obstruction is presented to the free movement of the paper section until it reaches the supporting members 1.

Promptly upon the arrival of the paper section in this position, an inward movement is given to the rear paper section supporting clamps 7 and to the opening members 8 and 9. The clamping action of the members 7 serves to smooth out and support the rear-most portion of the paper section and to hold the section as a whole in a firm upright position. The inward movement of the opening members 8 and 9 serves, as in the device shown in Patent No. 1,202,914, already referred to, to initially open the intermediately held paper section as the members close in on it. Having accomplished the initial opening of the paper section in the inward movement, the opening members 35 now act to engage the initially separated parts of the paper section and swing outwardly to complete the opening of this end of the paper section. At the same time the rear supporting clamps 7 also swing apart 40 whereupon the air continuously blowing from the nozzle 4, entering between the folds at their front separated end, forces them apart throughout their length. At the same time the guide members 12 are swung downwardly between the upper edges of the opened section through the reciprocating movement of the rods 90 and this movement is accompanied by the downward sweep of the two pairs of guiding members, or blades 50 12 to insure the complete separation of the folds of the paper section and to guide the descending insert into place in the opened section.

It will be seen that this operation has included the initial straightening out of the folded paper section by means of a blast of air as a section passes downwardly to a position of rest on the supporting member 1. This step was followed by the clamping of 60 the rearmost part of the paper between the rear supporting clamps 7 and the initial opening of the folded front edges of the section as the opening members 8 and 9 were brought to closed position. The next step 65 was the separation of both the rear support-

ing clamps 7 and the movable members 8 and 9 to complete the opening of the front portion of the paper section with the aid of the air blast issuing from the nozzle 4 whereupon the immediate operation of the blades 70 12 guided the descending insert into place.

The mechanism which is carried by the opening members 8 and 9 for initially and then finally opening the paper sections follows in a general way the corresponding 75 mechanism shown in the Patent No. 1,202,914 but differs therefrom in some particulars.

By reference to Fig. 2 of the drawing, it will be seen that a pair of opening devices are provided which are arranged to be operated in alternation. The opening members 8 and 9 of the two opening devices A and B are pivoted on the shafts 13 and 14. The hub of the opening member 9 of the opening device A has extending horizontally 80 therefrom in opposite directions the arms 15 and 16. The arm 15 is arranged to be connected to a vertical reciprocating rod 17 which is designed to operate both opening devices A and B. The other arm 16 engages 85 through a pin and slot connection 18 with the end of the corresponding arm 19 projecting from the hub of the opening member 9 of the opening device B. In addition to the described connection between the two 90 opening devices there are shown connecting rods 20 and 21 which connect the outside movable members of the two opening devices to each other and the inside opening members of the two opening devices to each 95 other so that the opening members are caused to operate in unison. It will be seen therefore that an operation of the operating arm 13 which will move the opening member 9 of the opening device A of Fig. 2 to closed 100 position will cause a simultaneous movement of the opening member 9 of the other opening device B to an open position through the operative connection between the arms 16 and 19. The movement of the 110 movable member 9 of the opening device A to the right causes through the connecting rod 21 a corresponding movement of the movable member 8 of the other opening device B to the right, or its closed position. 115 Also the movement of the opening member 9 of the opening device B to the right, or its open position, causes a corresponding movement of the movable member 8 of the opening device A to the right, or its closed position, through the connecting rod 20.

That feature of the invention which comprises means for performing the initial opening of the folded paper section preferably takes the form of a buckling member, or 125 roller, 25 which is provided with a friction paper engaging surface and is adapted to be rocked upon its axis as it engages the paper section to thereby cause a buckling of the fold of the section with which it directly 130

engages. The buckling roller 25 is preferably supported in a bracket 26 which is pivotally mounted on the rod 27 carried by the movable member 9 of each of the opening devices. The bracket 26 which carries the buckling roller 25 is preferably normally held in an upright position by means of a spring 28 acting against a fixed collar 29 on the rod 30 which is attached to the bracket 26 at 31. The bracket 32 carried by the framework provides a stop member for the lower end of the spring 28 and a slide-way through which the rod 30 may operate. It will be seen that an upright position of the bracket 26 will cause a corresponding projection of the buckling roller 25 to the left, or to a position where it will be extended beyond the face of the opening member upon which it is carried so that it will engage the paper section before the supporting member has arrived at the limit of its closing movement. The provision of the spring 28 provides, however, for the yielding movement of the buckling member when it encounters the thrust of the opposing opening member 8. In addition to the pivoted supporting bracket 26 which carries the buckling roller 25, there is provided also a link member 23 pivoted at 24 on the movable member 9 and connected at its upper end to a horizontal link 34 which is pivoted in turn to the upper end of the pivoted bracket 26. It will be seen that a parallel motion is thus provided which will direct the bodily movement of the buckling roller 25 into engagement with the paper engaging member 65 of the opening member 8, which is preferably pivotally mounted so that it can adjust itself to the surface of the paper section. In order to turn the buckling member about its own axis in order to give the roller a movement relative to the paper section in order to buckle the same, a rigid arm 35 extending upwardly from the movable member 9 is connected through a link 36 with a crank 37 attached to one end of the shaft 38 on which the buckling roller 25 is mounted. It will be seen that by this arrangement the bodily movement of the buckling roller to the right will provide a relative movement of the crank 37 about its axis thereby giving a rotative movement to the buckling roller 25. At the same time that the buckling member was moving into engagement with the paper section the clamping member 56, formed by the end of the bracket 32 carried on the member 9, was moved into position to clamp the paper section between the member 56 and the yielding member 54. The clamping member 54 is preferably pivoted on the rod 27 carried by the opening member 8 and in swinging rearwardly about its pivot on the rod 27 has the effect of drawing taut the fold of the paper section engaged thereby, as is clearly shown in Fig. 5. This pulling effect is secured by the downwardly rubbing action of the face of the clamping member 54 and is useful in that it assists in confining the buckling action solely to the unstretched 70 fold.

The folded paper section having been initially opened by the operation just described, the completion of the opening operation is now performed. As a preliminary 75 to this operation the reciprocating fingers 39 are projected into the opening 40 between the folds of the paper section which was produced by the buckling operation as shown in Fig. 5 of the drawing. The means 80 for bringing about this step in the operation comprises the reciprocating finger supporting blocks 41 slidably carried by the rods 27 as shown in Fig. 1. The blocks 41 have extensions coöoperating with a guideway 85 formed in the arc-shaped laterally extending guide member 42. The provision of this device provides for the lateral movement of the two rods 27 as they are carried to and from each other by the corresponding movement of the opening members by which they are supported. The provision of the guide member 42 serves also as a means for giving a reciprocating movement to the fingers 39 parallel to the rods 27. The movement of 90 the guide member 42 is brought about through the vertical reciprocation of a rod 43 which rocks a bell crank 44 about its pivot and thereby transmits movement to a link 45 connecting the end of the bell 100 crank 44 and a connecting member 46, see Fig. 2, carried by the guide member 42. It will be seen that while the reciprocating fingers of one opening device are operated by the arrangement just described, the reciprocating fingers of the other opening device are operated by the corresponding reciprocating rod 47 and a bell crank 48 acting through a link 49 and a connecting member 50. This difference in the arrangement of 110 the operating devices for the two sets of reciprocating fingers provides for the alternate operation of the two devices, by a movement of the vertical operating rods 43 and 47 in the same direction. It will be obvious 115 that it is necessary to cause one set of fingers to be projected into position while the other set is being withdrawn therefrom in the alternate operation of the two opening devices.

The preliminary outward movement of the opening members serves to clamp the paper section between the holding devices 51 and 52 and the adjacent fingers 39. Both the clamping members 51 and 52 are held 120 out of paper engaging position while the opening members are in closed position but are spring pressed to position to grip the paper against the sides of the fingers 39 with the beginning of the movement of the open- 130

ing members to separated position. In order to hold the clamping member 51 out of paper engaging position during the buckling operation, an extension 53 from the 5 clamping member 51 is arranged to be engaged and pushed rearwardly by the lower yielding clamping member 54 acting through the adjustable stop screw 55 seated in the lower end of the extension 53.

10 An expansion spring 57 mounted on the bolt 58 exerts a thrust against the laterally extending arm 59 of the clamping member 51 thereby tending to move this clamping member, as well as the lower one 54, through 15 the extension 53, to a projected position. The nuts 59' threaded on the upper end of the bolt 58 provide a convenient means for regulating the thrust exerted by the spring. A second spring 60 mounted on the end of 20 the bolt 58 which extends below the fixed supporting lug 61 exerts a thrust against the abutment 62 on the lower clamping member 54. An adjustable collar 63 on the rod 58 forms a suitable abutment for the 25 upper end of the spring. An adjustable stop screw 106 coöperates with a lug 107 on the clamping member 54 to limit the forward projection of the clamping member.

In order to remove the clamping member 30 52 from paper engaging position this clamping member is preferably mounted on an arm 52' carried by the shaft 38 of the buckling roller 25 so that the clamping member 52 is swung rearwardly to retracted position with the turning of the buckling member about its axis as the opening members 8 and 9 close in on each other. It will be clear 35 that the thrust of the spring 28 on the pivoted bracket 26 will have the effect of swinging the buckling member 25 together with the clamping member 52 to normal position as the opening member 9 begins its swinging movement away from closed position.

In the operation of the device the initial 40 swinging apart of the opening members 8 and 9 permits the springs 57 and 28 to swing the respective clamping members 51 and 52 into position to clamp the folds of the paper section into engagement with the fingers 39, as has been noted, and the immediately following outward swinging movement of the opening members serves to carry the folds of the corresponding end of the paper section to its completely separated 45 position. This operation is accompanied by the opening of the rear paper section clamping members 7 which permits the stream of air blowing from the nozzle 4 to separate the folds of the paper section from end to end. 50 The immediate swinging of the guiding blades 12 downwardly between the separated folds of the paper section directs the insert sections into place, whereupon the reciprocating fingers 39 are withdrawn from their

clamping engagement with the folds of the 65 paper section and the released and completely assembled paper is gripped between the feeding-out rolls 10 and 11 and discharged downwardly between the guide strips 66. 70

The feeding-out rolls 10 are preferably mounted to rotate with a shaft 67 on which they are carried and which is driven through a suitable coupling connection as shown at 68 in Fig. 1 from any suitable drive shaft 69. 75 The shafts 67 are preferably carried on the arms 70 which are adapted to be rocked in unison by the jointed operating rods 71 driven from any suitable source of movement through the arm 72. One of the rods 71 preferably passes freely through lugs 73 carried on the sides of the rear pair of arms 70 and carries the springs 74 which provide for a yielding movement of the arms 70 in 80 one direction.

The idle feeding-out rollers 11 are carried on rock arms 75 carried by the rock shaft 76. The arms 75 are also arranged to be operated by the operating rod 71 which is pivotally connected to the arms 96 at 77 whereby the 90 shaft 76 and arms 75 are rocked. It will be seen that the arms 75 which carry the feeding out rollers 10 are in effect levers of the first class while the other two arms which carry the driven feeding-out rollers 11 are 95 levers of the third class, so that an arrangement has been provided whereby the single operating rod 71 is enabled to operate both sets of feeding-out rollers in alternation, in 100 correspondence with the operation of the opening members 8 and 9.

In order to direct the paper sections to the opening devices in alternation and in accordance with their opening movement, a switch 80 has been provided which is adapted to be swung from one side to the other to direct the papers which are being fed through the passageways 81 to the switch channel 81' either to the branch passage 82 or 83 to the corresponding opening device. Preferably, in the normal operation of the device, cover sections are fed from either passageway 81 into the switch channel 81' in alternation with insert sections which are simultaneously fed from both passageways 81 into an associated relation in the switch channel. In the timing of the parts the switch 80 is swung to the opposite side of the switch channel immediately following the passage of a cover section therethrough. The cover section is fed down through the branch passage 82 or 83 to the corresponding spring device which is at this moment in its open position. Meanwhile the following insert section which was directed into the other branch passage is similarly fed downwardly into a cover section which has been opened to receive it. The passage of

the insert section into place is followed by the feeding through the same branch passage of a cover section before the position of the switch is changed and this cover section drops into place between the opened jaws of the opening device immediately following the discharge of an assembled paper therefrom, the ejecting rollers 10 and 11 being brought to operating position while the opening members 8 and 9 remain in their opened position. The operation just described takes place alternately in one or the other opening devices in accordance with each reversal of the switch 80, as will be obvious. The switch is driven in any suitable manner through the arm 84 and reciprocating rod 85 in properly timed relation with the remaining moving parts. The feed rolls 86 are preferably driven through intermediate pinions 87 which coöperate with feed rolls 88 to feed the paper sections through the channels 82 and 83.

The manner of operating the paper supporting members 1 is best shown in Figs. 1 and 6 of the drawing. The supporting members 1 are pivotally mounted on the shafts 76 which carry the feeding-out roller supporting arms 15 and each of the members 1 has an upwardly extending lug 91 carrying a roller 92 adapted to be engaged by the end of one of the operating arms 93. The arms 93 are pivotally mounted on vertical axes as at 94 and each has a lug 95 extending beyond the pivot for engagement by one of the arms 96 mounted on the rock shaft 76 and adapted to be operated by the connection with the operating rod 71. It will be seen that each of the arms 93 can thus be swung about its pivot 94 to cause the end thereof to engage the roller 92 carried by the lug 91 of the supporting member 1 and thereby swing the supporting member into or out of supporting position.

The specific mechanism for operating the paper supporting clamps 7, which are preferably mounted on spring pressed plungers 107, is best shown in Fig. 6 of the drawing. This mechanism follows very closely the construction of the mechanism for operating the opening members 8 and 9 illustrated in Fig. 2.

The arms 96' and 97 which carry the clamping members 7 are pivotally mounted on the stud shafts 98 projecting from the rear framework of the machine. The hub of the arm 97 of the opening device A has extending horizontally therefrom the arms 99 and 100. The arm 99 connects to a vertically reciprocating drive rod 101. The other arm 100 engages through a pin and slot connection at 102 with an arm 103 projecting from the hub of the clamp-carrying arm 97 of the opening device B and thereby conveys motion to the right-hand set of clamps. The

arms 96' of the device A and the arm 97 of the opening device B are respectively connected together by means of the link 106 and the arm 96' of the device B and the arm 97 of the device A are connected together by the lug 105 so that the arms of the two opening devices are caused to operate in unison. It will be seen that a movement of the operating arm 99 that will swing the arm 97 of the opening device A to closed position will, through the connection of the arms 100 and 103, move the right-hand arm 97 to open position. Also the movement of the arm 97 of the opening device B to open position will pull the arm 96 of the opening device A to the right, or its closed position, through the link 106 as will be obvious. A corresponding movement of the arm 97 of the device A to open position will close the arm 96 of the device B through the link 105.

What is claimed, is:

1. An opening device comprising: means movable toward and from each other and toward and from an intermediate folded paper section, said means including devices for engaging and clutching the respective folds of the paper section whereby the paper section will be opened as the movable means move away from each other, and means for directing a blast of air into the opening between the folds of the section to assist in the opening thereof.

2. An opening device comprising: means movable toward and from an intermediate folded paper section, said means including devices for engaging and clutching a comparatively restricted area of the respective folds of the paper section whereby the paper section will be opened at the engaged portion as the movable means move away from each other, and means for directing a blast of air into the opening between the folds of the section to assist in the opening thereof.

3. An opening device comprising: means movable toward and from each other and toward and from one end of an intermediate folded paper section including devices for opening the end of the section, means for introducing a blast of air between the folds at the opened end of the section to open the section throughout its length, and insert guiding means arranged to move into the opened section.

4. An opening device comprising: means movable toward and from each other and an intermediate folded paper section, said means including devices for initially opening the paper section as the movable means move toward each other and other devices for completing the opening of the section as the movable members move away from each other.

5. An opening device comprising: jaws for closing against the opposite folds of an

intermediate folded paper section, said jaws including devices for clutching the respective folds of the paper section, means for swinging the jaws apart to thereby form an opening between the folds of the section, and means for directing a blast of air into the opening to completely open the section.

6. An opening device comprising: jaws for closing against the opposite folds of an intermediate folded paper section, said jaws including devices for initially separating the folds of the section as the jaws move to closed position, said jaws also including devices for clutching the initially separated folds of the paper section, means for swinging the jaws apart to thereby form an opening between the folds of the section, and means for directing a blast of air into the opening to completely open the section.

10. An opening device comprising: movable members arranged to be closed against the opposite folds of an intermediate folded paper section, said members including devices for clutching the respective folds of the paper section, means for moving the members apart to thereby form an opening between the folds of the section, means for directing a blast of air into the opening to completely open the section, and means arranged to move into the opened section to guide an insert into place therein.

15. An opening device comprising: means for supporting a folded paper section in a vertical position with its fold lowermost, means movable toward and from each other and the intermediately supported paper section and including devices for initially opening the folded paper section as the movable means approach each other, and means carried by said movable means for clamping the folds of the initially opened section to the movable means, whereby the paper section is completely opened as the movable means move away from each other, and 45 means for blowing a stream of air between the folds of the section as the movable means move apart.

20. A paper section opening apparatus comprising: two opening devices, each opening device including a pair of opening members movable toward and from each other, and means for causing the members of one opening device to move to closed position as the members of the other opening device move to opened position and vice versa.

25. A paper section opening apparatus comprising: two opening devices, each opening device including a pair of jaws movable to and from each other, and means interconnecting the jaws of the two opening devices so that the movement of one pair of jaws to closed position moves the other pair of jaws to open position and vice versa.

30. A paper section opening apparatus

comprising: two opening devices mounted side by side, each opening device including a pair of jaws movable to and from each other and generally to and from the jaws of the other device, and means connecting the adjacent jaws of the two devices to each other and the remaining jaws of the two devices to each other, whereby the movement of one pair of jaws to closed position moves the other pair of jaws to open position and vice versa.

35. An opening device comprising: members movable to and from with relation to each other and to an intermediate folded paper section, means carried by said members for stretching one fold of said paper section taut, and means carried by said members for buckling the remaining fold of said paper section to initially open the paper section.

40. An opening device comprising: members movable to and from with relation to each other and to an intermediate folded paper section, and means carried by said members for clamping said folded paper section adjacent the folded edge and adjacent the open edge, the clamping means engaging the folded edge of said section being operable to stretch one of the folds of said section taut, and the clamping means engaging the open edge of the section being operable to buckle the remaining fold, whereby the section is initially opened.

45. An opening device comprising: members movable to and from with relation to each other and to an intermediate folded paper section, and means carried by said members for clamping said folded paper section adjacent the folded edge and adjacent the open edge, the clamping means for engaging one fold of the section near the folded edge being movable outwardly toward the folded edge to stretch the engaged fold taut, and the clamping means for engaging the remaining fold of the section near the open edge being movable inwardly away from the open edge to buckle the last-named fold, whereby the paper section is initially opened.

50. An opening device comprising: members movable toward and from each other and an intermediate folded paper section, means carried by said members for stretching one fold of said paper section taut, means carried by said members for buckling the remaining fold of said section to initially open the section, and means for completing the opening of the section.

55. An opening apparatus for a paper assembling machine comprising: means movable to and from with relation to each other and to an intermediate folded paper section, and an opening device carried by one of said members and movable with relation

thereto to initially open the paper section as the members move to the paper engaging position, the movement of said opening device relative to the member on which it is mounted being effected by the direct thrust of the other member.

17. An opening apparatus for a paper assembling machine comprising: members movable to and from with relation to each other and to an intermediate folded paper section, a pivotally mounted opening device carried by one of said members for ini-

tially opening the paper section as the members move to paper engaging position, the opening device being arranged to move with relation to the member on which it is mounted as it encounters the thrust of the other member, and means for rocking the opening device on its pivot as it moves with relation to its supporting member.

Signed at New York in the county of New York and State of New York this 13th day of November A. D. 1916.
